UNITED STATES PATENT OFFICE.

LEWIS MILLER AND JACOB MILLER, OF CANTON, OHIO.

IMPROVEMENT IN GRAIN-CLEANERS.

Specification forming part of Letters Patent No. **33,956**, dated December 17, 1861.

To all whom it may concern:

Be it known that we, LEWIS MILLER and JACOB MILLER, of Canton, in the county of Stark and State of Ohio, have invented certain new and useful Improvements in Grain-Cleaning Machines; and we do hereby declare that the following is a full, clear, and exact description of the construction and operation of the same, reference being had to the accompanying drawings, making a part of this specification, in which—

Figure 1 represents a perspective view of the machine. Fig. 2 represents a longitudinal vertical section, and Fig. 3 represents an end view.

Similar letters of reference where they occur in the separate figures denote like parts in all the drawings.

Our invention consists, first, in suspending the shoe by straps that are hinged at one end and fast at the other end, but working like a spring, for the purpose of giving a steady noiseless motion to the shoe and screen without any sudden blow or jar.

It further consists in combining with a shoe and screen suspended by straps, that are hinged at one end and have a springing motion at the other end, a spring-pitman for operating them that is also made fast to said shoe, so as to prevent any sudden jar or blow or wearing of joints, which produces excessive motion and noise.

It further consists in a pair of adjustable wind-boards, the lower one of which has a lip or return upon it to prevent the grain from running over the trough or spout which conducts it out of the machine.

It further consists in regulating the blast at the end of the riddle by hanging the front end of the riddle in adjustable bearings, by which the space between it and the grain-board of the shoe may be increased or diminished, as circumstances may require.

To enable others skilled in the art to make and use our invention, we will proceed to describe the same with reference to the drawings.

A B represent the sides of the machine. At the rear of the machine is the fan-chamber C, in which a fan D is revolved by a crank E, or otherwise. Near the end of the fan-shaft there is a bevel-pinion which works

into the bevel-wheel F on the shaft G, and this shaft G has upon its end a crank-wheel H, for shaking the shoe I and screen J by means of a spring-pitman J', that is made fast to said shoe, so as to avoid the wear and consequent noise that would occur if this connection were made by a loose joint of any kind. The crank-wheel may have a series of holes 1 2 3 at different distances from its center, into either one of which the pitman may be placed, and by this means the extent of vibration of the shoe or riddles may be adjusted at pleasure.

K L are upper and lower wind-boards, which are hinged, respectively, to the fan-case at a b by means of canvas, leather, or any other flexible material that will keep the hinged joint secure against the escape of the blast; and the ends of these wind-boards have small arms projecting through slots c cut in the sides of the frame, on which arms hand screw-nuts d are run, so that they may be adjusted from the outside of the machine and increase or diminish the force of the blast as well as to direct it more to or from the front end of the screen or riddle. The lower wind-board L has a return lip or flange e hung to it, which when the wind-board is moved also moves, but keeps constantly close to the spout or trough M, and thus prevents any grain from running over the trough.

The shoe I is suspended to the sides of the frame by straps f, that are hinged at i, the lower ends of said straps being rigidly fastened to the shoe, as at n. The lugs m, to which the straps are hinged, may be adjustable so as to raise or lower the shoe, and adjustable fastenings may also be made at the lower ends of the straps, as at o, for a similar purpose.

The front end of the riddle or screen J has slotted brackets r upon it, by means of which and set-screws s the space and consequently the blast between the riddle at this end and the grain-directing board N may be increased or diminished at pleasure. A door O may be made in this grain-board N, which is held closed by buttons t t, for gaining access to the interior of the machine.

The grain to be cleaned is fed into the machine from a hopper in the usual manner, and it falls upon the inclined board B, and,

running down upon the vibrating fingers *u*, is loosened up, so as not to choke the riddle. The grain passes through the riddle and is cleaned by the blast, it falls through below said riddle, and passing down the grain-board *N* runs into the trough *M*, and thence out of the machine. The straw, chaff, &c., pass over and out from under the riddle and fall into the trough *Q*, whence they are carried off to any desirable point.

Having thus fully described our invention, what we claim therein as new, and desire to secure by Letters Patent, is—

1. Suspending the shoe of a grain-cleaning machine to the frame by means of straps that are hinged at one of their ends and have a springing motion at the other end thereof for producing a regular but noiseless motion to the shoe, substantially as described.

2. In combination with a shoe suspended

by straps that are hinged at one end and have a spring motion at the other end, a spring-pitman for vibrating said shoe without sudden jar or noise, substantially as described.

3. The adjustable wind-boards *K L*, the latter having a lip or flange *e*, constructed and operating substantially as herein described, and for the purpose set forth.

4. Hanging the front of the riddle in adjustable bearings, so that it may be moved to or from the grain-directing board *N*, for the purpose of regulating the blast with regard to that end of the riddle, substantially as described.

LEWIS MILLER.
JACOB MILLER.
